UNITED STATES PATENT OFFICE

PAUL D. REDCAY, OF PHILADELPHIA, PENNSYLVANIA, ASSIGNOR, BY MESNE ASSIGNMENTS, TO UNION SPECIAL MACHINE COMPANY, OF CHICAGO, ILLINOIS, A CORPORATION OF ILLINOIS

THREAD SEVERING MECHANISM FOR LOOPING MACHINES

Application filed September 28, 1928. Serial No. 309,024.

This invention relates to a thread severing mechanism for use in connection with a looping machine of the type employed for uniting parts of stockings or other knit work, or fabric wherein the parts of the stockings or other knit work are united by a continuous chain of stitching which must be severed at points between the stockings.

The object of the invention is to provide an improved severing device for such a looping machine which will automatically sever the chain of stitching that unites the several stockings or other knit fabric on the machine so that the projecting threads at each side of the sewed stocking, which is left, after the severing operation, will be of a substantial uniform length.

A further object of the invention is to provide a severing mechanism in combination with an automatically operated feeding means for feeding the loose chain of stitches between the stockings into the path of the severing mechanism.

Further objects of the invention will appear more fully hereinafter.

The invention consists substantially in the combination, construction, arrangement and relative location of parts, all as will be more fully set forth as illustrated in the accompanying drawings and finally pointed out in the appended claims.

Referring to the accompanying drawings in which the same or similar parts have been referred to in the various views by the same reference numerals,

Figure 1 is a side elevational view, partly in section, of sufficient of a looping machine, to illustrate my thread severing device applied thereto.

Fig. 2 is a plan view of the mechanism illustrated in Fig. 1.

Fig. 3 is a side elevation of the thread severing device taken on the line 3-3 in Fig. 2, looking in the direction of the arrows.

Fig. 4 is a side elevation of the thread severing device taken on the line 4-4 in Fig. 2 looking in the direction of the arrows.

Fig. 5 is an end view of the thread severing device.

Fig. 6 is a detail side elevational view of

the cutting blades of my thread severing device.

Machines for uniting or sewing together the parts of knit goods such as stockings, of the type to which my thread severing device is applied, are well known in the art and it is thought unnecessary to show herein or describe in detail the complete construction and operation thereof. An illustration of a machine of this general type is shown and described in the patent to Merrow, No. 330,606, dated November 17, 1885. It is sufficient to say that generally machines of this type are provided with a circular bed or support having a stitch forming mechanism positioned with respect to said bed or support so that its stitch forming elements operate over a circular movable work supporting member which is rotatably supported on the circular bed or support. The movable work supporting member carries a series of radially projecting impaling pins which move with said support past the stitch forming mechanism.

In the operation of the machine the portions of the stockings or other knit fabric to be united are placed on the impaling pins in such a manner that the edges of the same project slightly above the impaling pins and the stitch forming mechanism operates to place a line of stitching in the projecting edges of the stockings or other knit fabric as the movable work supporting member causes the same to pass within the field of action of the stitch forming mechanism. The articles to be stitched in this manner are usually placed upon the impaling pins a slight distance apart.

The stitching mechanism is continuously operated, and therefore the threads carried by it will extend continuously from one article to another just above the impaling pins. When the stitched articles are removed from the impaling pins it is therefore necessary to sever these connecting threads between the articles. This is accomplished either by hand or by mechanism provided for that purpose.

In the drawings illustrating my improved cutting device, I have only shown sufficient of such a looping machine to illustrate the ap-

lication of my invention thereto. Referring to the drawings, the circular bed or support of the machine is indicated at 1. Said support is fixedly secured by a nut 2 or other suitable means to a stud 2a carried by the end of an arm 3 which is positioned over the support and mounted at its other end in a suitable manner to the base of the machine. The movable work supporting member is indicated at 4. The impaling pins carried by said movable work supporting member are shown at 5 and project radially from said movable supporting member in the usual well known manner.

15 The thread severing mechanism of my invention is mounted at any suitable point on the circular bed or support 1 beyond the stitch forming mechanism. The said mechanism may be operated from any suitable moving part of the machine. One proposed means for operating the same is illustrated in the drawings and will be described hereinafter.

20 The operating parts of the severing mechanism are supported by a bracket member 6 which is secured to the circular bed or support of the machine by means of the screw 7. Said bracket member is provided with an outwardly extending arm 9 which may be formed integral with said bracket member or detachably secured thereto by a screw 8 or other suitable means.

25 The free end of said arm 9 carries a short rotatable shaft 10. Fixedly secured to said shaft is the ratchet wheel 11 and the circular brush 12.

30 Pivotedly secured to bracket member 6 as at 13 is a cam shaped member 14 having a projection 15. The cam shaped member is also pivotally secured as at 15a to a pawl member 16. The free end of said pawl member is adapted to engage the teeth of the ratchet wheel 11 and is held in engagement with the teeth of said ratchet wheel by means of a spring 17 which is secured at one end to said pawl member and at the other end to the pin 18 mounted in said supporting bracket 6.

35 Mounted on said bracket member 6 is a stationary cutting member 19 which is integrally secured to said bracket and is positioned so that its cutting edge extends adjacent to the impaling pins 5 on the movable work support member 4 and behind the edges of the article imposed on the impaling pins.

40 The pin 18 mounted in supporting bracket 6 passes through the stationary cutting member 19 and supports the movable cutting member 21. The movable cutting member is positioned with respect to the fixed cutting member 19 so that its cutting edge has a shearing action with the cutting edge of said member 19 and is held in such shearing position by nut 20.

45 The movable cutting member is provided with a rearwardly extending arm 22 which is

adapted to engage an eccentric 23 mounted on a shaft 24. The shaft 24 is rotated in any suitable manner by the main operating shaft of the machine.

50 The arm 22 of the movable cutting member is so positioned with respect to the cam shaped member 14 that the projection 15 thereof engages the same. The cam shaped member is held in engagement with said arm 22 by means of the spring 25 which is secured to said cam shaped member and said movable arm. Also secured between the arm 22 and the circular base plate is the spring 26 which is adapted to normally hold said arm so that the cutting edge of the movable cutting blade is closed with respect to the cutting edge of the stationary cutting member.

55 The operation of the cutting mechanism described above is as follows: After a stocking or other article imposed upon the impaling pins has been stitched by the stitching mechanism thus forming a slightly projecting stitched portion or welt it passes to the cutting mechanism. The eccentric 23 which is continuously rotated on shaft 24 actuates the arm 22 of the movable cutting member causing said cutting member to rock on the pin 18 so as to have a shearing action with the fixed cutting member 19. The movement of the arm 22 of the movable cutting member also causes the cam shaped member 14 to actuate the pawl 16 so that it rotates the ratchet wheel 11 and consequently rotates the circular brush 12. The brush is so positioned with respect to the impaling pins 5 that in rotating it brushes across the same inwardly and towards the cutting edges of the cutting members 19 and 21.

60 As each one of the stitched articles passes by the cutting mechanism the brush sweeps the connecting thread 29 between such stitched article and the next stitched article, inwardly, into the field of action of the cutting edges of the cutting members and it is at once severed. In view of the relative positions of the several parts it can be seen that the thread is severed at substantially equal distances from the knitted articles.

65 In order to insure the thread extending between the stitched articles being swept into the path of the cutting members a guard 28 may be secured to the plate 27 which may be mounted on the pin 18 of the supporting bracket and held in place by said nut 20 and a guard 31 may be mounted on an extension 32 secured to said supporting bracket so that the brush will sweep the thread between said guard and the impaling pins into the path of the cutting members.

70 It will be seen that by the action of the several parts of the above described severing mechanism that the stitching thread which extends between the stitched articles will be severed positively and automatically and the projecting threads at each side of the

sewed article after the severing operation will be of a substantially uniform length.

Having now fully described my invention, what I claim as new and desire to secure by Letters Patent is:

1. A sewing machine including in combination work suspending and feeding means, a thread cutting mechanism comprising a stationary cutting blade, a movable cutting blade and devices for operating the same, all disposed at one side of the plane of travel of the fabric sections, a brush located above said fabric sections and rotating about a horizontal axis, and means for intermittently rotating said brush in timing with the operation of the movable cutting blade for placing enchain'd thread loops between the cutting blades while said blades are separated.
2. A sewing machine including in combination work suspending and feeding means, a thread cutting mechanism comprising a stationary cutting blade and a movable cutting blade, a spring for moving said blade for severing the enchain'd threads placed between the cutting blades, a rotating device for separating the cutting blades, a brush rotating about a horizontal axis and located above the travel of the fabric sections, and means for intermittently rotating the brush operated by the movable cutting blade and timed so as to place the enchain'd thread loops between the cutting blades while they are separated.

35 In testimony whereof I have hereunto set my hand on this 24th day of September A. D., 1928.

PAUL D. REDCAY.
